THOMAS A. CAMPBELL, OF NEW YORK, N. Y.

Letters Patent No. 98,922, dated January 18, 1870.

IMPROVEMENT IN APPARATUS FOR OILING WOOL

The Schedule referred to in these Letters Patent and making part of the same.

To all whom it may concern:

Be it known that I, THOMAS A. CAMPBELL, of the city, county, and State of New York, have invented a new and useful Improvement in Devices for Oiling Wool, and other fibrous material, in carding and other machines, of which the following is a full, clear, and exact description, reference being had to the accompanying drawing, forming part of this specification, and in which—

Figure 1 represents a plan view of a device or apparatus constructed in accordance with my improvement;

Figure 2, a transverse section thereof, through the line $z-z$ in fig. 1; and

Figure 3, an end view of a compressor or pair of compressing-plates employed in supplying the oil to a revolving brush or sprinkler, with motion attached for operating said compressor, or the one plate thereof.

Similar letters of reference indicate corresponding parts.

My improvement relates to devices or apparatus for the sprinkling of oil in a fine and uniform manner on the wool, or other fibrous materials, for operation in connection with carding and other machines:

The invention embraces a novel manner, or means therefor, of supplying the brush or sprinkler with the oil, whereby the use of rollers or lifting-mechanism, operating by adhesion for said purpose, is dispensed with. In such connection, the invention includes a compressing-plate or plates having a squeezing-action, and a pad or pads and cushions to the acting-surface or surfaces thereof.

Likewise, the invention comprises a certain and advantageous combination and arrangement of an oil-tank with said compressing-plates, and drip-way to prevent waste.

When the apparatus is applied to a carding-engine, it may be set on the feed-table thereof, and the wool be conveyed by an apron, over which the apparatus is arranged, and where it may be secured to the sides of the feed-table. If applied to a picker, it may be located at the delivery-portion thereof.

In the accompanying drawing—

A represents the oil-tank, and

B, the revolving brush or sprinkler, which is driven by a pulley, a .

On the brush-shaft b is an eccentric, c , for communicating motion, by a strap and rod, d , and arm or crank, e , to a shaft, f , arranged over the tank, and which serves, as it is rocked, to operate, by arms g , and link-rods h , the oil-lifting device, which is made up of compressing-plates, $C C'$, the one (C) of which only need be made to move on side or end bearings $i i$, in adjustable connection, by screws and slotted arms

These plates $C C'$ are set in moderately close relation to each other, inclining upward from the rear of the tank, and dip at their lower edges, which may be bent, into the oil in the tank.

The upper or working-plate C is faced with a pad or cushion, k , of cloth or other suitable material.

By the arrangement of the plates $C C'$, and that of the studs or bearings $i i$, near the upper edge of the working-plate, as shown, said working-plate C , when lifted, allows the oil in the tank to enter or flow between the plates $C C'$, which are then opened below and closed above. In the downward movement of the plate C , this position of the plates is reversed, that is, they are closed below and opened above. Such double action of the upper plate, relatively to the lower one, produces a squeezing-action on the oil, the squeezing or compressing-action taking place when the upper plate or portion thereof below its bearings is depressed, and which compression causes the oil, previously caught and held in between the plates, to be delivered in a fine or thin film out of, or from between the upper edges of the plates. The pad or cushion k aids in producing lift on the oil during the reverse movement of the upper plate, and retention of the same between the plates during the return-action of said upper plate, which opens above, to deliver oil, when it closes below, and vice versa.

The forcing or compressing-action of the plates $C C'$ being continued, a free or full supply of oil is kept up to the revolving brush B throughout its entire length, the quantity being regulated by the adjustment of the plates relatively to each other, and stroke of the working-plate. The brush, thus supplied, is so arranged, that the outer portions of its bristles are caused to impinge on the projecting lip or upper edge of the lower plate C' , whereby the oil, as the brush revolves, is formed into fine spray, and thrown upon the wool passing beneath.

The lower plate C' is raised above the edge of the oil-tank, and so set as to allow the drip, if any, to return into the tank, to again mix with the contents thereof, and should the brush not take up all the oil forced up between the plates $C C'$, or delivered by them, such surplus is caused to flow back over the top or working-plate, which is bevelled on its upper edge, and beyond which the lower plate projects, the oil thus returning to the tank, mixing with the contents of the latter, and keeping the body of oil well mixed. The drip-way, and provision for the return of the surplus oil, also prevent waste of the same.

Of course, other liquids, besides oil, may be worked in like manner by the apparatus.

What is here claimed, and desired to be secured by Letters Patent, is—

1. The combination of compressing-plates, acting as

oil or liquid-lifters from the tank, in the manner described, with a revolving brush or sprinkler of the oil or liquid thus lifted, substantially as specified.

2. The combination of a pad, *b*, with the compressing-plates *C C'*, or working-plate thereof, when arranged and operating essentially as described.

3. The combination, construction, and arrangement, relatively to each other, of the compressing-plates *C*

C', and the tank *A*, whereby dripping or surplus supply of oil or liquid is returned to the tank, and the mixing of the contents of the latter kept up, substantially as specified.

THOMAS A. CAMPBELL.
